United States Patent Office

Des. 223,988

Patented June 27, 1972

223,988

PLUG SPANNER

Charles C. Robinson, 20 Martindale Ave.,
Wimborne, England

Filed Aug. 20, 1970, Ser. No. 24,593

Term of patent 14 years

Int. Cl. D8—05

U.S. Cl. D8—27

FIG. 1 is a perspective view of a plug spanner showing my new design.

FIG. 2 is a fragmentary perspective view of the plug spanner of FIG. 1 but from the opposite side; and

FIG. 3 is a fragmentary side elevation of the plug spanner of FIG. 1.

FIG. 4 is a fragmentary side elevational view showing the handle portion of the plug spanner.

I claim:

The ornamental design for a plug spanner, as shown.
